United States Patent Office

Des. 215,840
Patented Nov. 4, 1969

215,840

BED-SOFA

Tomasina Kukura, 8009 Hollywood Blvd.,
Hollywood, Calif. 90046

Filed May 6, 1968, Ser. No. 11,801

Term of patent 14 years

Int. Cl. D6—01

U.S. Cl. D15—11

Fig. 1.

Fig. 2.

Fig. 3.

FIGURE 2 is a similar view showing my design in its couch forming condition, and

The ends of the design are identical.

I claim:

The ornamental design for a bed-sofa, as shown and described.
